US0D1036942S

(12) **United States Design Patent** (10) **Patent No.:** **US D1,036,942 S**
(45) **Date of Patent:** **** Jul. 30, 2024**

(54) **PICNIC BASKET COOLER**

(71) Applicant: **Igloo Products Corp.**, Katy, TX (US)

(72) Inventor: **John Maldonado**, Katy, TX (US)

(73) Assignee: **Igloo Products Corp.**, Katy, TX (US)

(**) Term: **15 Years**

(21) Appl. No.: **29/787,872**

(22) Filed: **Jun. 9, 2021**

(51) **LOC (14) Cl.** **07-10**

(52) **U.S. Cl.**

USPC **D7/605**; D7/709

(57) **CLAIM**

The ornamental design for a picnic basket cooler, as shown and described.

DESCRIPTION

FIG. 1 is a top, front, right side perspective view of a picnic basket cooler, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the figures illustrate portions of the picnic basket cooler that form no part of the claimed design.

1 Claim, 7 Drawing Sheets
